UNITED STATES PATENT OFFICE.

ANNA M. BRASINGTON, OF CLEVELAND, OHIO.

COMBINATION-UNDERGARMENT.

No. 851,796.

Specification of Letters Patent.

Patented April 30, 1907.

Application filed January 7, 1907. Serial No. 351,261.

To all whom it may concern:

Be it known that I, ANNA M. BRASINGTON, a citizen of the United States, residing at Cleveland, in the county of Cuyahoga and State of Ohio, have invented certain new and useful Improvements in Combination-Undergarments, of which the following is a specification.

My invention relates to skirted under-garments for women in which waist and skirt are integral, as in skirted union garments; and my object is to provide a single garment which shall serve as a bodice or corset cover, full-front waist, shirt-waist holder and skirt-holder, bustle support, and attachment for removable flounces, skirt bottoms or petticoats.

Much discomfort is experienced in warm weather, especially by stout persons, from the necessity of wearing a multiplicity of undergarments about the shoulders, waist and hips; and I obviate this difficulty by the garment shown in the drawings, in which—

Figure 1 is a front view of the entire garment, a portion being broken away to show my improved manner of attaching the removable flounces; Fig. 2 is a rear view of the upper portion of the garment, showing the waist- and skirt-securing tab and the manner of attaching the bustle; Fig. 3 is a vertical dorsal section at about the waist line, showing more clearly the attachment of the tab and bustle; Fig. 4 is a horizontal section of the waist at about the bust line, showing the construction of the close fitting waist portion and the manner of attaching the full front; and Fig. 5 is an enlarged sectional view taken along the line 5—5 of Fig. 1 and showing the manner of constructing and attaching the flounces and providing a covering tuck or flap for such attachment.

In the various figures, 1 represents the waist portion, preferably sleeveless and low-necked, and 2 the hip portion of the garment. Both these are of a single thickness of suitable material, and preferably fitting the figure closely. Along the side lines of the waist, as at under-arm seams if such are used, are attached the pieces 3 extending thence to the front of the waist and provided at top and bottom with shirring cords or tapes 4. Intermediate tapes, (not shown), may be provided, if desired, either as additional securing means or for ornamentation solely.

At the back of the waist portion, at about the waist-line, is attached a tab 6 of strong

material, having an unattached depending portion 7; said tab forming a pinning piece for holding in position the outer- or shirt-waist and also for securing and supporting the belt of the outer or dress skirt.

At the back, below the waist line, and on the inside of the garment, is provided a plurality of buttons 8 (four such buttons being shown); to which may be attached a pad or bustle 9. This feature is of particular advantage to stout or large-hipped persons who are usually correspondingly flat-backed; and the pad aids materially in giving a proper hang to the skirts.

That portion of the garment thus far described terminates preferably about midway between the hip and knee, as shown, though it will be understood that this length may be varied as desired; and the lower edge is furnished with buttons 10, arranged in zigzag or "staggered" relation. These buttons are preferably hidden and protected by a tuck or flap 11, as most clearly shown in Fig. 5.

The detachable flounces, petticoats, or skirt-bottoms 12 are provided at the top with a button-hole strip, preferably scalloped at the upper edge as at 14, and having the button-holes arranged, of course, in a zigzag or staggered row.

So far as I am aware, detachable flounces heretofore used have been provided with a single straight row only of button-holes; and when attached to a straight row of buttons, no matter how closely spaced, the strip will invariably sag or bulge outwardly between the buttons, rendering the attachment unsightly and inconveniently thick and bulky. In my manner of attachment, by giving the upper edge of the button-hole strip between the alternate holes of the row a curve approaching a natural catenary curve, the supporting buttons may be placed a considerable distance apart and the lower edge of the strip will then be held smoothly in place by the intermediate buttons without any tendency to sag or bulge outwardly, even with a plurality of wide and comparatively heavy flounces attached thereto.

In the drawing, I have shown two flounces or skirt bottoms attached to the strip; but it will be apparent that as many as desired may be so attached. It is also apparent that the entire garment may be trimmed to suit the fancy of the wearer.

The garment described has the advantage of combining in a single light body-garment a

close-fitting, supporting bodice, a full-front underwaist which gives the requisite fullness to the outer shirt-waist, a rear attachment for shirt-waist and skirt-belt, a bustle-support, and an underskirt or petticoat, while reducing to a minimum the number of thicknesses of fabric about the hips. All these features are of particular advantage in warm weather. In addition thereto, as many flounces or skirt-bottoms may be attached as may be desired or necessary to give fullness to the outer skirt, without discomfort to the wearer; and if soiled about the bottom, these flounces may be readily detached and separately laundered. The manner of attachment is such that the petticoat skirts are held as firmly and smoothly as if supported from a belt at the waist.

It is apparent that many changes may be made in the garment without departing from my invention; since what I claim is:—

1. An undergarment comprising a close-fitting bodice and a comparatively-short, skirted extension made of a single thickness of fabric; the lower part of said skirted extension being provided with two rows of buttons, the buttons of one row being substantially opposite the middle of the space between the buttons of the other row, and a flounce-supporting strip having a scalloped upper edge and suitably positioned button-holes, said strip being adapted to carry one or more flounces and to be attached to said single skirted-extension; substantially as described.

2. An undergarment having an upper

skirted portion of a single thickness of fabric, and provided at its lower edge with a double or zigzag row of buttons, in combination with an attachable flounce strip having button-holes corresponding to the button-arrangement of the upper skirt portion, and one or more flounces attached to said strip.

3. An undergarment having an upper skirted portion provided at its lower edge with a double or zigzag row of supports, in combination with an attachable strip having a scalloped upper edge and a double or zigzag row of coöperating supports; said strip having secured thereto one or more flounces.

4. An undergarment comprising a close-fitting bodice and a comparatively-short, skirted extension made of a single thickness of fabric; said bodice portion having a rearwardly-attached, skirt-holding tab, and said skirted extension having interior, attached bustle-supporting means and being provided near its lower edge with a zigzag row of buttons and a covering flap therefor, in combination with an attachable flounce or petticoat member comprising a button-hole strip having a scalloped upper edge and a zigzag row of button-holes and having attached to its lower edge one or more flounces; substantially as described.

In testimony whereof I affix my signature in presence of two witnesses.

ANNA M. BRASINGTON.
